UNITED STATES PATENT OFFICE

125,906

DESIGN FOR A HYDRAULIC JACK OR THE LIKE

Clifford M. Akins, Minneapolis, Minn.

Application December 27, 1940, Serial No. 97,894

Term of patent 7 years

To all whom it may concern:

Be it known that I, Clifford M. Akins, a citizen of the United States and a resident of Minneapolis, in the county of Hennepin and State of Minnesota, have invented a new, original, and ornamental Design for a Hydraulic Jack or the like, of which the following is a specification, reference being had to the accompanying drawing, forming a part thereof.

Figure 1 is a perspective view of a hydraulic jack or the like showing my new design with the handle in partly raised position; and

Figure 2 is a side elevational view thereof with the handle in raised position and looking from the opposite side with respect to Figure 1.

The dominant features of my design reside in the portion of the drawing shown in solid lines.

I claim:

The ornamental design for a hydraulic jack or the like, substantially as shown and described.

CLIFFORD M. AKINS.
